COMPRESSOR

Arnold E. Biermann, Hampton, Va.

Application September 10, 1935, Serial No. 39,913

15 Claims. (Cl. 230—156)

This invention relates to gas compressors or power producing engines of the rotary type, and the main object is to provide a compressor or engine of compact construction and efficient 5 operation.

Owing to inherent features of construction the volume capacity of my device is much greater than that of other machines of this class having the same overall dimensions. In my device it is 10 possible to handle in a single cycle of operation several times the volume of the compression chamber.

An object of this invention as used for compressing fluids such as air is to provide in this 15 type of machine means for trapping and isolating each charge of gas to be compressed and means for reducing the volume of the trapped charge until the pressure is raised to a predetermined outlet pressure before communication 20 with the discharge port is established. To those familiar with the art it is evident that maximum efficiency is obtained in this type of compression. Work is done against a pressure which increases 25 continuously from the inlet pressure to the discharge pressure.

In all previous pumps of this class compression of the induced charge takes place with the charge in constant communication with the discharge port. Work is always done against the 30 full discharge pressure. As is well known in the art, such a condition gives rise to a square indicator card and is very inefficient.

Furthermore, in these last mentioned pumps throttling losses occur when the high pressure 35 gas in the discharge line rushes back into the chamber containing the low pressure charge. These throttling losses are not present in my device as communication is not established between the chamber in which the charge is being compressed and the discharge line until the pressure 40 in the former is raised to that of the latter.

A further object of this invention is to provide means in this type of gas compressor for varying the point of intake cut-off and in this manner 45 control the quantity of gas pumped. In consequence, the power required for compression is very nearly proportional to the quantity of fluid pumped. Other compressors of this class, due to properties inherent in their construction, must 50 resort to other means of control such as throttling the intake. It is evident that in these other compressors the power required may be much in excess of the power required to compress the quantity of gas desired.

55 The compactness, efficiency, and controllability

of my device make it especially desirable for supercharging aircraft engines. In this service it is necessary to provide means for changing the volume capacity of the compressor to meet the requirements at various altitudes.

Another object of this invention is to provide a suitable and ready means for changing from a compressor to an engine or from an engine to a compressor, the same means being also adapted to changing the compression ratio when used as a compressor and the point of exhaust opening when used as an engine.

In the accompanying drawings Figure 1 is a side view in elevation and partly in section of a compressor constructed in accordance with the principles of my invention; Figure 2 is a view in perspective of a rotor, rotor shaft, and impeller assembly; Figure 3 is a diagrammatic view to show the principles of operation; Figure 4 is an end view in elevation with the housing partly cut away; Figure 5 is a view in perspective of a rotary valve; Figure 6 is a view in perspective of a rotary valve control sleeve; Figure 7 is a view in perspective of a sleeve cam for manually controlling the rotary valve port opening.

Referring to Figures 1 and 4, 1 designates a housing constructed in two parts, fastened together to form a torus-like chamber to which are attached the spiral abutments 2. Side members 3 and 4 are secured to housing 1 as shown in Figure 1 and serve as bearing supports for the rotor shaft 5 and also provide means for attaching respective intake and discharge pipes.

Referring now to Figures 1, 2 and 4, the rotor 6 is fixed to the rotor shaft 5 by means of the rotor shaft flange 7. The outer rim of the rotor 6 is circular and constructed to provide bearings 8 for the impeller shafts 9. The impellers 10 are mounted on shafts 9 and are adapted to rotate through the slots 11 provided in the web and rim of the rotor 6. The impellers 10 are provided with the radial slots 12 which associate with the spiral abutments 2. These slots are relieved sufficiently at the outer portions as to allow rubbing contact with the spiral abutments 2 only at the inner slot portions 13 where the angle between the impellers 10 and the spiral abutments 2 is more favourable for rotation of the impellers by the abutments.

Referring to Figures 1 and 4, each spiral abutment 2 extends from one side of the web 14 of the rotor 6 around the torus-like housing 1 in spiral fashion to the opposite side of the web 14. The shape of each spiral abutment 2 is such as would be generated by the slot 12 of an im-

eller 10 as the impeller moves with the rotor 6 at a uniform speed about the axis of the rotor while at the same time the impeller 10 rotates about its own axis at a uniform speed such as 5 to generate a predetermined number of whole spiral abutments in one revolution of the rotor.

This manner of generation gives the device a smoothness of operation but requires that the abutments be made of thickness varying along 10 their lengths. This results from the fact that the angle of the spiral occupied by the abutments varies from a minimum nearest the rotor axis to a maximum where it is farthest from that axis.

The angle of slot 12 through impeller 10, however, is fixed; and where the direction of slot 15 motion deviates most from its angle, the slot will develop the thinnest shape for the abutments.

Referring to Figures 1, 4 and 5, the rotary valves 15 and 16 are of similar construction and 20 are secured to the rotor web 14 for rotation adjacent to the base portion 17 of the spiral abutments 2.

The rotary valves 15 and 16 are constructed with a series of ports 18 and 19. The valve portions 25 20 and 21 between the ports are parallel to the adjacent spiral abutments 2. The width of the ports 18 and 19 is less than the width of the base portion 17 of the spiral abutments 2.

Referring to Figures 1, 5, 6 and 7, control 30 sleeves 22 and 23, which are of similar construction, are rotatably mounted inside and adjacent to the rotary valves 15 and 16 and are provided with openings 24 and 25. The sleeves 22 and 23 provide a means for adjusting the expansion and 35 compression ratio of the compressor, adjustment being accomplished by rotation of the sleeves relative to the rotary valves 15 and 16 respectively. Any suitable means may be utilized for controlling the angular position of sleeves 22 and 40 23. For purposes of illustration I show and describe a simple manually controlled means which is of similar construction for both sleeves 22 and 23. Sleeve cams 33 are rotatably mounted on shaft 5 and are fastened to the control sleeves 45 22 and 23. Said sleeve cams are provided with the cam slots 32. Control shafts 26 are slidably mounted in hole 27 in shaft 5 and are provided with pins 28 adapted to extend through slots 30 in shaft 5 and through cam slots 32 in sleeves 33. 50 Collars 34 are slidably mounted on shaft 5 and are fastened to control shafts 26 by means of pins 29 passing through the slots 31 in shaft 5. Collars 34 are provided with a groove 35. Forked 55 levers 36 are pivotally mounted in side members 3 and 4 and are provided with pins 37 extending into grooves 35. It is evident that movement of forked levers 36 causes control shafts 26 to slide axially in the shaft 5 and by means of pins 28 extending into cam slots 32 of 60 sleeves 33 causes angular movement of control sleeves 22 or 23 with respect to the rotary valve 15 or 16 respectively.

The torus-like housing 1 is provided with ribs 38 for strengthening and to obtain additional 65 cooling area.

The operation of my invention is as follows:— As the rotor 6 rotates, association of the impellers 10 with the spiral abutments 2 causes rotation of the impellers 10 about their axes. In 70 this movement the portion of each impeller 10 between spiral abutments 2 sweeps each chamber formed by the spiral abutments 2, the housing 1, the rotor 6, the intake valve 15 and the discharge valve 16.

75 The detailed cycle of operation is best under-

stood by means of the diagrammatic view shown in Figure 3. In this view the inside of the torus-like housing is stretched out flat showing the spiral abutments 2, the impellers 10, the rotary intake valve 15, the discharge valve 16, the intake valve control sleeve 22 and the discharge valve control sleeve 23.

In operation as a compressor the impellers 10, the rotary valves 15 and 16, and the control sleeves 22 and 23 effectively move in the direction shown by the arrows while the abutments 2 and the housing 1 remain stationary.

It will be noticed in Figure 3 that when the impellers arrive at a position in which the chamber volume is a minimum the inlet ports also arrive at the same chamber and establish communication with that chamber. Then as the impeller moves to increase the size of the chamber additional ports communicate with the chamber and gas is inducted. When the last inlet port which is exposed by the control sleeve 22 has passed the chamber the charge is trapped and is expanded and then compressed as the chamber volume passes through its maximum. When the discharge ports arrive at the chamber communication is established with the chamber and the gas is forced out of the chamber by the impeller. It will be noticed that the position of the intake valve control sleeve 22 regulates the interval of the cycle that the chamber is in communication with the inlet pipe and so regulates the quantity of gas trapped in the chamber. The position of the discharge valve control sleeve 23 regulates the point in the cycle when open discharge ports 19 arrive at the chamber and therefore regulates the degree to which the charge is compressed before communication is established with the discharge pipe.

To further illustrate the operation, A is a 40 chamber just receiving gas through the rotary intake valve 15 and control sleeve 22; the chamber B is still receiving gas but is nearing the point of cut-off; in C the gas has been trapped and expanded to its full volume; the gas in D 45 is being compressed; while in E the compressed gas is being discharged through the rotary valve 16 and the control sleeve 23.

It is evident from Figure 3 that moving the control sleeve 22 on the inlet side forward will 50 cause cut-off to occur at a smaller chamber volume resulting in a smaller quantity of gas being trapped in each chamber. Moving the control sleeve 23 forward on the discharge side opens those discharge ports which communicate with the chamber at a larger chamber volume and therefore results in a decreased chamber pressure at discharge. Obviously rearward movement of the control sleeves produces the opposite effects. In this manner it is possible to control both the weight of gas compressed and the compression pressure for any speed of operation of the compressor.

For these reasons it is evident that such a compressor is especially useful as a supercharger for an internal combustion engine. Furthermore when used in conjunction with an internal combustion engine at part load the supercharger may be used as an engine for taking part of the engine load by adjusting the control sleeves to give a 70 discharge pressure less than the intake pressure. The supercharger is thus used at part engine loads to throttle the intake to the engine and the work which is done by the gas on the supercharger in expanding from the inlet pressure to 75

the engine manifold pressure effects an increase in overall efficiency.

The specific construction shown in the illustrations is characterized by having impellers provided with two slots to each impeller and having three times as many abutments as impellers. Although this construction has certain advantages it is to be understood that I do not wish to confine my invention to any specific combination 10 of abutments and impellers.

What I claim is:

1. In a device of the class described a housing having a torus-like recess, one or more spiral abutments fixed to the surface of the housing 15 within said recess, a rotor mounted for rotation in said housing in close association therewith to form a toroidal chamber, one or more impellers mounted for rotation in said rotor and adapted to move in close association with said spiral 20 abutments and the surfaces of said housing and rotor to form substantially gas-tight compartments adapted to vary in volume cyclically from zero to a maximum and to zero again as the rotor is revolved, inlet ports in said rotor adapted to 25 provide communication with said compartments only during expansion of said compartments from zero to a given volume, outlet ports in said 30 rotor adapted to provide communication with said compartments only during contraction of said compartments from a given volume to zero volume, and means for selectively adjusting each of said given volumes to any value between zero and the said maximum.

2. In a device of the class described a housing 35 having a torus-like recess, one or more spiral abutments fixed to the surface of the housing within said recess, a rotor mounted for rotation in said housing in close association therewith to form a toroidal chamber, one or more impellers 40 mounted for rotation in said rotor and adapted to move in close association with said spiral abutments and the surfaces of said housing and rotor to form substantially gas-tight compartments adapted to vary in volume cyclically 45 from zero to a maximum and to zero again as the rotor is rotated, inlet ports in said rotor adapted to provide communication with said compartments during expansion of said compartments from zero to a predetermined volume, means for varying the size of the inlet ports 50 for controlling the maximum volume attained by the compartments while still in communication with the inlet ports, outlet ports in said rotor adapted to communicate with said compartments 55 during contraction of said compartments from a predetermined volume to zero, and means for varying the outlet port size for controlling the volume of the compartment at which communication is first established with the outlet.

3. In a device of the class described a housing having a torus-like recess, one or more spiral abutments fixed to the surface of the housing within said recess, a rotor mounted for rotation in said housing in close association therewith to 60 form a toroidal chamber, one or more impellers mounted for rotation in said rotor and adapted to move in close association with said spiral abutments and the surfaces of said housing and rotor to form substantially gas-tight compartments 65 adapted to vary in volume cyclically from zero to a maximum and to zero again as the rotor is rotated, inlet ports in said rotor adapted to provide communication with said compartments during expansion of said compartments from 70 zero to a predetermined volume, means for vary-

ing the size of the inlet ports for controlling the maximum volume attained by the compartments while still in communication with the inlet ports, outlet ports in said rotor adapted to communicate with said compartments during contraction of 75 said compartments from a predetermined volume to zero volume.

4. In a device of the class described a housing having a torus-like recess, one or more spiral abutments fixed to the surface of the housing within said recess, a rotor mounted for rotation in said housing in close association therewith to form a toroidal chamber, one or more impellers mounted for rotation in said rotor and adapted to move in close association with said spiral abutments and the surfaces of said housing and rotor to form substantially gas-tight compartments adapted to vary in volume cyclically from zero to a maximum and to zero again as the rotor is rotated, inlet ports in said rotor adapted to provide communication with said compartments as 10 said compartments vary in volume from zero to a predetermined volume, outlet ports in said rotor adapted to communicate with said compartments as said compartments vary in volume from a predetermined volume to zero, and means for varying the outlet port size for controlling the volume of the compartments at which communication is 15 first established with the outlet.

5. In a device of the class described a housing having a torus-like recess, one or more spiral abutments fixed to the surface of said housing within said recess, a rotor mounted for rotation in said housing in close association therewith to form a toroidal chamber, one or more slotted 20 impellers mounted for rotation in said rotor and adapted to move in close association with said spiral abutments and the surfaces of said housing and rotor to form compartments adapted to vary in volume as the rotor is rotated, the slots 25 of said impellers being relieved at the outer portions a sufficient amount to allow rubbing contact of the impellers with the tip portions only of said spiral abutments.

6. In a device of the class described a housing having a torus-like recess, one or more spiral abutments fixed to the surface of the housing within said recess, a rotor mounted for rotation in said housing in close association therewith to form a toroidal chamber, one or more impellers mounted for rotation in said rotor and adapted to move in close association with said spiral abutments and the surfaces of said housing and rotor to form substantially gas-tight compartments adapted to vary in volume as the rotor is rotated, 30 inlet ports in said rotor extending from each impeller in the direction opposite to the direction of rotation of the rotor a predetermined distance, a movable control sleeve mounted adjacent to said inlet ports to vary the distance said inlet ports extend from the impellers, outlet ports in said rotor extending from each impeller in the direction of rotation of the rotor a predetermined distance, a movable control sleeve mounted adjacent to said outlet ports to vary the distance 35 said outlet ports extend from the impellers, grid bars extending across said inlet and outlet port openings in a direction parallel to the adjacent spiral abutments and spaced to provide openings between said grid bars not less than the thickness of the adjacent portion of said spiral abutments.

7. In a device of the class described a housing having a torus-like recess, one or more spiral abutments fixed to the surface of the housing 40

within said recess, a rotor mounted for rotation in said housing in close association therewith to form a toroidal chamber, one or more impellers mounted for rotation in said rotor and adapted 5 to move in close association with said spiral abutments and the surfaces of said housing and rotor to form substantially gas-tight compartments adapted to vary in volume as the rotor is rotated, inlet ports in said rotor extending from each 10 impeller in a direction of rotation opposite to the direction of rotation of the rotor a predetermined distance, a movable control sleeve mounted adjacent to said inlet ports to vary the distance said inlet ports extend from the impellers, outlet 15 ports in said rotor extending from each impeller in the direction of rotation of the rotor a predetermined distance, a movable control sleeve mounted adjacent to said outlet ports to vary the distance said outlet ports extend from the 20 impellers.

8. In a device of the class described a housing having a torus-like recess, one or more spiral abutments fixed to the surface of the housing within said recess, a rotor mounted for rotation 25 in said housing in close association therewith to form a toroidal chamber, one or more impellers mounted for rotation in said rotor and adapted to move in close association with said spiral abutments and the surfaces of said housing and rotor 30 to form substantially gas-tight compartments adapted to vary in volume as the rotor is rotated, inlet ports in said rotor extending from each impeller in the direction opposite to the direction of rotation of the rotor a predetermined distance, 35 a movable control sleeve mounted adjacent to said inlet ports to vary the distance said inlet ports extend from the impellers, outlet ports in said rotor extending from each impeller in the direction of rotation of the rotor a predetermined 40 distance.

9. In a device of the class described a housing having a toroidal chamber, one or more spiral abutments fixed to the surface of said chamber, a rotor mounted in said housing for rotation with 45 respect to said toroidal chamber, one or more impellers rotatably mounted in the rotor and adapted to move in close association with respect to said spiral abutments and the surface of said toroidal housing, said impellers, spiral abutments 50 and housing combining to form chambers of variable volume, ports in said toroidal housing communicating with said toroidal chamber, a rotary valve fixed to each side of said rotor and having ports of variable size for communication 55 with any chamber of variable volume in said toroidal housing during prescribed intervals in the cycle.

10. In a device of the class described a housing having a torus-like recess, a disc rotatably mounted in said housing, said disc having an enlarged 60 rim section, rotary valves mounted to turn with said disc and to fit in close association with said recessed housing to form a toroidal chamber, spiral abutments fixed to the surface of said 65 torus-like recess and extending from one side of said disc to the opposite side, slotted impellers rotatably mounted in the rim of said disc in engagement with said toroidal chamber and spiral abutments to form compartments of varying volume as said disc is rotated, the slots of said slotted 70 impellers being relieved at the outer portions a sufficient amount to allow rubbing contact with the free edge portion only of said spiral abutments, inlet and outlet means in said rotary 75 valves on opposite sides of said disc providing

communication with said compartments only during prescribed intervals in the rotation of said disc.

11. A device of the class described comprising a housing having a torus-like recess, a disc 5 mounted for rotation in said housing, rotary intake and discharge valves mounted concentrically with respect to said housing and on opposite sides of said disc and extending therefrom to fit in close association with said recessed housing to 10 form a toroidal chamber, means for supporting and rotating said disc, slotted impellers mounted in the rim of said disc, spiral abutments of longitudinally varying thickness attached to the inner surfaces of said housing and so disposed as to 15 continually fit said slots of said impellers as said impellers rotate about their axes and revolve with said disc simultaneously, ports in said intake and discharge valves of variable size for communication with any portion of said housing only 20 during prescribed intervals in the cycle.

12. In a device of the class described a housing having a torus-like recess, a disc rotatably mounted in said housing, said disc having an enlarged rim section, rotary valves mounted to 25 turn with said disc and to fit in close association with said recessed housing to form a toroidal chamber, spiral abutments fixed to the surface of said torus-like recess and extending from one side of said disc to the opposite side, slotted impellers rotatably mounted in the rim of said disc 30 in engagement with said toroidal chamber and spiral abutments to form compartments of varying volume as said disc is rotated, said disc being constructed of two similar parts providing means 35 when fastened together for mounting said slotted impellers in the rim of said disc, inlet and outlet port means in said rotary valves on opposite sides of said disc providing communication with said compartments only during prescribed intervals 40 in the rotation of said disc.

13. In a device of the class described a housing having a torus-like recess, spiral abutments fixed to the surface of said housing, a slotted disc mounted for rotation in said housing, rotary intake and discharge valves mounted concentrically with respect to said torus-like housing and on opposite sides of said disc and extending therefrom to fit in close association with said recessed housing to 45 form a toroidal chamber, slotted impellers rotatably mounted in the rim and slots of said disc in engagement with said housing and spiral abutments forming substantially gas-tight compartments wherein the volume is varied 50 cyclically from zero to a maximum and to zero again as said disc is rotated, intake ports in said rotary valve on one side of said disc providing intake means into said compartments during expansion of said compartments from zero to a given volume, discharge ports in the other said 55 rotary valve providing discharge means from said compartments during contraction of said compartments from a given volume to zero volume.

14. In a device of the class described a housing having a torus-like recess, a disc rotatably mounted in said housing, said disc having an enlarged rim section, rotary valves mounted to turn with said disc and to fit in close association with said recessed housing to form a toroidal chamber, spiral abutments fixed to the surface of said 60 torus-like recess and extending from one side of said disc to the opposite side, slotted impellers rotatably mounted in the rim of said disc in engagement with said toroidal chamber and spiral abutments, said spiral abutments being one more 65

in number per said impeller than there are slots per impeller.

15. In a device of the class described a housing having a torus-like recess, a disc rotatably mounted in said housing, said disc having an enlarged rim section, rotary valves mounted to turn with said disc and to fit in close association with said recessed housing to form a toroidal chamber, spiral abutments fixed to the surface of said torus-like recess and extending from one side of said disc to the opposite side, slotted impellers rotatably mounted in the rim of said disc in engagement with said toroidal chamber and spiral abutments to form compartments of varying volume as said disc is rotated, inlet and outlet port
- means in said rotary valves on opposite sides of said disc providing communication with said compartments only during prescribed intervals in the rotation of said disc, adjustable control sleeves mounted adjacent to said inlet and outlet ports to vary the distance said ports extend from said impellers, and grid bars extending across said inlet and outlet port means in a direction parallel to the adjacent spiral abutments and which are spaced to provide openings between said grid bars of a width not less than the thickness of the adjacent portion of said spiral abutments. 5 10

ARNOLD E. BIERMANN.
